KEYBOARD FOR AN INFORMATION PROCESSING UNIT OR THE LIKE

Dean C. Bowman, Oklahoma City, Joe R. Waldrop, Beth-
any, and George B. Webb, Oklahoma City, Okla., as-
signors to General Electric Company, a corporation of
New York

Filed Oct. 20, 1967, Ser. No. 9,085

Term of patent 14 years

Int. Cl. D14—02

U.S. Cl. D26—5

FIG. 1

FIG. 2

FIG. 3

FIG. 4

FIG. 1 is a left side, top and front perspective view of a keyboard for an information processing unit or the like showing our new design;

FIG. 2 is a right side elevation of the same;

FIG. 3 is a left side elevation of the same; and

FIG. 4 is a top plan view of the same.

The dominant features of my design reside in the portions shown in full lines.

We claim:

The ornamental design for a keyboard for an information processing unit or the like, as shown and described.
